The Lowell Manufacturing Company, of the same place.

Letters Patent No. 4942-Dated May 16, 1864.

Design for a Carpet Pattern.

These Schedule referred to in these Letters Patent and making part of the same.

To all whom it may concern:

Be it known that I, Elmer Key, of Lowell, in the County of Middlesex and State of Massachusetts, have originated and designed a new Pattern for Carpets or other fabrics, of which the following is a full, clear and exact description, reference being had to the accompanying drawings, making part of this specification.

A is an oblong block resting on the ground 1, which also supports groups of sprigs and Persian leaves and flowers.

The frame 3 encloses the ground 1, and is composed of a vine running between the inner and outer bands.

3 and 4, at the sides when matched form a block similar to A, resting on a ground similar to the ground 1.

5 and 6, when matched form a frame similar to frame 2.

Connecting frame 3 with the half frames 5 and 6, are the broad bands Band C, which are composed of blocks, zig-zag lines, half rosettes, and straight and waving lines, arranged as shown in the drawings.

D is a rosette surrounded by the double frame 7, from which radiate branches of leaves and sprigs.

The remaining parts of the drawing are sections of figures similar to those before specified.

DES. 1942

The colors employed for the different portions of the design may be varied to suit the taste and wish of the manufacturer.
